US0D1040141S

(12) **United States Design Patent** (10) **Patent No.:** **US D1,040,141 S**
(45) **Date of Patent:** **** Aug. 27, 2024**

(54) **WIRELESS EARPHONES WITH CHARGING CASE**

(71) Applicant: **Shenzhen Zhongbaile Technology Co., Ltd**, Shenzhen (CN)

(72) Inventor: **Ying Liu**, Shenzhen (CN)

(73) Assignee: **Shenzhen Zhongbaile Technology Co., Ltd**, Shenzhen (CN)

(**) Term: **15 Years**

(21) Appl. No.: **29/940,224**

(22) Filed: **Apr. 30, 2024**

(51) LOC (14) Cl. **14-01**

(52) U.S. Cl.

USPC **D14/223**; D13/108

(58) **Field of Classification Search**

(57) **CLAIM**

The ornamental design for a wireless earphones with charging case, as shown and described.

DESCRIPTION

FIG. 1 is a top perspective view of a wireless earphones with charging case, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of the charging case of the wireless earphones with charging case thereof, shown separately for ease of illustration;

FIG. 10 is a bottom perspective view thereof;

FIG. 11 is a front view thereof;

FIG. 12 is a rear view thereof;

FIG. 13 is a left side elevational view thereof;

FIG. 14 is a right side elevational view thereof;

FIG. 15 is a top view thereof;

FIG. 16 is a bottom view thereof;

FIG. 17 is a top perspective view thereof, of the wireless earphones with charging case; and,

FIG. 18 is a bottom perspective view thereof, of the wireless earphones with charging case.

The broken lines in the drawings illustrate the portions of the wireless earphones with charging case, which form no part of the claimed design.
